ABSTRACT OF THE DISCLOSURE

Apparatus for making metal tubes of square or rectangular cross-section having ribs or flutings swaged thereon spaced at regular intervals comprising, in combination, a press for preferably operating simultaneously on two opposite faces of the tube, and a mandrel insertable into said tube, said mandrel having dies mounted pivotably thereon, cooperating with said press, and disengageable from the internal tube faces whereby a longitudinal displacement of said tube with respect to said mandrel can occur between swaging operations.

This application is a division of copending U.S. patent application Ser. No. 329,758, filed Dec. 11, 1963, now abandoned.

It is well known that tubes of square or rectangular cross-section facilitate the assembly of tubular frameworks. On the other hand, the flat faces of such tubes are prone to sustain local distortions due to crippling or punching.

It is the chief aim of the present invention to overcome such drawbacks.

The invention accordingly has for its object a tube of square or rectangular cross-section, of which at least one face, and preferably two opposite faces or possibly all four faces, embody swaged flutings spaced at regular intervals over a portion at least of the length of the tube.

Such swaged flutings reinforce the tube faces on which they are provided and their shape could be such as to liken such tube faces to what is common practice in the art of structural steelwork and metal frameworks, namely lattice girders of Virsandel girders.

In cases where a local force tending to distort one of the flat fluted faces is applied, its action tends to be transmitted by the flutings, whose shape is particularly appropriate for withstanding transverse compression forces in particular.

The flutings are swaged inwardly into the tube, in consequence whereof the external face of the tube is devoid of raised portions, thus enabling flat surfaces to be joined together.

The flutings are obtained during manufacture of the tubes and their shape can vary greatly. For instance, they could be perpendicular to the axis of the tube or be inclined relative thereto in the same direction or in alternating directions, or else they could be circular or rectangular. These flutings can be obtained with advantage by swaging industrial-type tubes, whose face usually have a width in excess of 150 millimetres.

The depth of a swaging which depends on the thickness of the sheet-metal could be of the order of $\frac{1}{40}$ of the width of the tube-face and its width could be equal to approximately one-tenth, say, of the width of the tube face.

Furthermore, the pitch, i.e. the mean distance between two consecutive flutings, as measured parallel with the tube axis, is substantially equal to the width of the tube face. Considering finally the tube itself, its length is im-

2

material, being for all practical purposes limited only by transport considerations. As stated precedingly, it may be preferable in certain cases to restrict the flutings to part only of the tube length.

The invention likewise encompasses apparatus for stamping flutings on industrial-type tubes of square or rectangular cross-section whereby to obtain the fluted tubes referred to hereinabove.

Such apparatus comprises basically a press that preferably operates on two opposite faces of the tube simultaneously, and a mandrel engaging into the tube. The mandrel supports dies and is devised to enable the same to be applied against the internal faces of the tube for cooperation with the press whereby to obtain the swagings and also to enable said dies to be disengaged from the internal faces of the tube after the swagings have been performed in order that the tube can be moved longitudinally relative to the mandrel and thereby enable a fresh swaging operation to commence.

In one form of embodiment of the invention, the mandrel comprises two yokes each having a die pivotally mounted thereon. The two yokes are interconnected at one end by an elastic member, and the spreading apart of the two yokes that causes said dies to be applied against the internal faces of the tube, as well as the subsequent contraction of the yokes that enables the dies to be disengaged from the tube faces, are obtained by means of a wedge-shaped axial member which is adapted to be insertable between said yokes and to be movable in reciprocation relative thereto.

The description which follows with reference to the accompanying non-limitative exemplary drawing will give a clear understanding of how the invention can be carried into effect.

Referring to the drawing filed herewith:

FIGURES 1 to 6 show schematically in longitudinal axial section a piece of apparatus for performing the desired swagings on a tube, said figures illustrating the respective positions of the various component parts in the course of a swaging cycle, and

FIGURES 7 to 11 show diagrammatically tubes embodying different types of flutings.

In FIGURES 1 to 6, reference numeral 1 designates an industrial-type metal tube of square or rectangular section, onto two of the faces of which it is desired to stamp flutings by means of a press whose operative components are schematically represented at 2a.

Reference numeral 3 denotes the mandrel which is inserted into the tube and comprises two yokes 4 and 4a having one of their ends pivotally connected at 5 and 5a to the body proper of the mandrel, which mandrel is a hollow core-piece whose outer diameter is substantially less than the internal dimensions of the tube. The other ends of yokes 4 and 4a are interconnected by a spring 6.

Each arm supports a shaft 7 (or 7a) parallel to the corresponding tube face into which the fluting or set of flutings is to be swaged. Dies 8 and 8a adapted to cooperate with the press members 2 and 2a are pivotally mounted on shafts 7 and 7a.

Between the yokes 4 and 4a is slidably a wedge-shaped member 9 having thereon inclined faces 10 and 10a adapted to cooperate with internal die faces of identical inclination 11 and 11a. Said member terminates in a tapered head 12.

The swaging apparatus of this invention operates in the following manner.

With the wedge-shaped member 9 in the retracted position relative to the yokes 4 and 4a, the mandrel is inserted into the tube until the dies are level with the press members 2 and 2a (see FIGURE 1), penetration of the mandrel into the tube being possible by reason of the maximum contraction thereof.

The wedge-shaped member 9 is then slid forward between the yokes 4 and 4a, thereby causing the latter to spread apart and the dies 8 and 8a to be applied against the internal faces of tube 1. As the wedge-shaped member 9 slides forward, its head 12 penetrates between the extremities of the yoke arms (see FIGURE 2). The penetrating motion of the wedge-shaped member 9 is pursued until its inclined faces 10 and 10a come into pressure contact with the corresponding inclined faces 11 and 11a of the dies. A rigid assembly inside the tube is thus obtained (see FIGURE 3).

The pressure exerted by the press members 2 and 2a causes the desired flutings to be swaged against the dies 8 and 8a, which dies are rigidly buttressed against the member 9 (see FIGURE 4).

It is to be noted that the slope of the faces 10, 10a, 11 and 11a is chosen so that the coefficients of friction between the various parts involved be sufficient to prevent the wedge-shaped member from being ejected during the swaging operation, but it will be manifest that the wedge-shaped member could be suitably restrained, if desired, during the swaging operation.

Once the swaging operation has been effected, the wedge-shaped member 9 is retracted in order to disengage its faces 10 and 10a from the corresponding inclined die faces (see FIGURE 5).

The retracting motion of the wedge-shaped member is continued until the mandrel reverts to the configuration shown in FIGURE 1, thereby enabling the tube 1 and its swaged flutings to be moved relative to the mandrel before it undergoes a fresh swaging operation (see FIGURE 6).

It goes without saying that the various operations, and more specifically the movements of the wedge-shaped member relative to the mandrel proper and of the tube relative to the mandrel, are obtained by conventional mechanisms that can be adapted to this particular function without difficulty by a specialist in the art.

Manifestly, the mandrel could support a plurality of sets of dies, or the dies could be of sufficient length to bear thereon a multiplicity of consecutive imprints.

It will of course be appreciated that if a press capable of operating over the entire length of a tube is to be used, it will suffice to so adapt the mandrel that it coact with the press during the simultaneous swaging of all the flutings. Alternatively, the flutings could be obtained by means of one or more rolling-mills in lieu of a press.

Irrespective of the method used, the tube flutings can be perpendicular to the tube axis as shown in FIGURE 7, 50 oblique or cruciform as shown in FIGURES 8 and 9 respectively, circular as shown in FIGURE 10, or rectangu-

lar as shown in FIGURE 11; alternatively, the flutings could be of any other appropriate shape.

What is claimed is:

1. Apparatus for making tubes of rectangular cross-section, more particularly for use in structural frameworks, having, on at least one of its faces, ribs or flutings swaged thereon and spaced at regular intervals over at least part of the length of the tube comprising, in combination, a press for preferably operating simultaneously on two opposite faces of the tube, and a mandrel insertable into said tube, said mandrel having dies mounted pivotably thereon and being so adapted that said dies be applicable against the internal tube faces for cooperation with said press for the swaging operation and disengageable from said internal tube faces subsequent to the swaging operation whereby to permit longitudinal displacement of said tube with respect to said mandrel and thereby to enable a fresh swaging operation to begin.
2. Apparatus as claimed in claim 1, wherein said mandrel comprises two yokes each having a die pivotally mounted thereon, said two yokes having one of their ends pivotally connected to a central core-piece and being interconnected at their other ends through the agency of spring means.
3. Apparatus as claimed in claim 1 wherein said die-bearing mandrel comprises two yokes having one of their ends pivotally connected to a central core-piece and having their other ends interconnected through spring means, and a wedge-shaped axial member adapted to be driven between said two yokes and to be retracted therefrom in a reciprocating motion relative to said two yokes.
4. Apparatus as claimed in claim 3, wherein said wedge-shaped member has inclined faces adapted to cooperate with inclined faces on said dies whereby to rigidly buttress the same during the swaging operation.
5. Apparatus as claimed in claim 4, wherein the slope of said inclined faces is chosen so that the coefficient of friction between the faces in contact be sufficient to prevent said wedge-shaped member from being ejected during the swaging operation.
